CLAIM

We claim the ornamental design for a tubular base for fans, as shown and described.

DESCRIPTION

FIG. 1 is a front perspective view of the tubular base for fans of the present invention;

FIG. 2 is a rear perspective view of the tubular base for fans of the present invention;

FIG. 3 is a front elevational view of the tubular base for fans;

FIG. 4 is a rear elevational view of the tubular base for fans;

FIG. 5 is a side elevational view of the tubular base for fans;

FIG. 6 is a side elevational view of the opposed side of the tubular base for fans;

FIG. 7 is a bottom view of the tubular base for fans; and,

FIG. 8 is a top view of the tubular base for fans.
